NICHOLAS W. HESS AND JACOB H. FRY, OF FORT WAYNE, INDIANA.

Letters Patent No. 78,829, dated January 14, 1868.

IMPROVEMENT IN WAGON-JACK.

The Schedule referred to in these Letters Patent and making part of the same.

TO ALL WHOM IT MAY CONCERN:

Be it known that we, NICHOLAS W. HESS and JACOB H. FRY, of Fort Wayne, in the county of Allen, and State of Indiana, have invented certain new and useful Improvements in Wagon-Jacks; and we do hereby declare that the following is a full, clear, and exact description thereof, reference being had to the accompanying drawings, and to the letters of reference marked thereon, in which—

Figure 1 is a side elevation, having one side removed.

The nature of our invention consists in an improved method of constructing wagon-jacks.

To enable others skilled in the arts to make and use our invention, we will proceed to describe its construction and operation.

A represents a curved lever, which is secured, by means of a fulcrum-pin, to the side pieces. The upper or outer end of this lever is so curved upward that it sets close to the body of the jack, as will be seen. The short arm of this lever extends inward horizontally, to the point or centre to which the weight is subjected. The lower end of this lever is made of cast iron, which is provided with a socket, *a*, into which a wooden handle is inserted. B represents a crescent-shaped link or step, the lower surface of which is provided with a projection, which serves as a hinge to secure it to the lever, as seen at *b*, said lever being so recessed to receive it, as seen in dotted lines. Link or step B supports upon its upper surface a lifter, C, the lower end of which is so formed as to fit into the concave upper surface of the step, said concave surface being a segment of a circle. Said lifter C is provided with two lugs, D, which take into and slide in grooves formed in the side pieces, as seen in dotted lines *c*. Said lugs and grooves act as guides to steady and keep the lower end of the lifter in position, and allow it to rise and fall perpendicularly to a limited distance. Guides, *f*, are also placed at or near the top of the side pieces, which serve to tie their tops together, as well as guide the movements of the lifter. The upper end of said lifter may be constructed as seen in the drawings, having a graduated series of elevated steps, one rising successively above the other, so as to accommodate different heights of axle-trees; or it may be constructed in any other desirable manner.

The operation of our wagon-jack is as follows: The lifter is placed under the axle, so that the jack stands vertical, and directly under the weight to be elevated. The lever is then forced backward and downward, until the end thereof strikes a line horizontal with the base of the jack. This movement elevates the inner or short arm of the lever, and with it the crescent-shaped step and lifter. In so doing, the step is caused to slide or revolve on the surface of the lower end of the said lifter, as will be readily understood. By this movement a rapidly-increasing power is obtained, as, while the lever is elevating the lifter, it is constantly shortening its short arm, which, when raised to its extremity, is almost perpendicular over the fulcrum. When the outer end of the short arm is so elevated that the fulcrum *d*, pivot of hinge *b*, and centre of crescent B, as seen at *f*, come in a straight line with each other, then the lifter has attained its greatest height, and the weight will be held at that point by the lever, should the outer end or long arm be relieved. But in order to give greater security, we carry the pivot *b* past this centre a short distance, until the concave end of the lever, as seen at *g*, strikes the convex surface of the crescent B at *h*, which takes the strain off from the pin, and securely supports it in its place. It will be observed, on inspection, that in addition to the increasing ratio of power gained by the shortening of the arm of the lever, as before described, we also combine a modification of the knee-joint lever, which commences to act at the point where the angle formed by lines *y y* and *z z* cross each other, form a right angle, and continues to act with accelerated force, until said lines run parallel, as seen in red lines, when the lifter is up, thus, in a word, bringing to bear on the weight a force that is unequalled in power, except by hydrostatic pressure.

What we claim as new, and desire to secure by Letters Patent, is—

The lever A, the concavo-convex or crescent-shaped step or link B, in combination with the convex surface of the stud or lifter C, the same being constructed in the manner and for the purpose described.

NICHOLAS W. HESS, [L. S.]
JACOB H. FRY. [L. S.]
